S. T. SANFORD.

Metal Punch.

No. 8,660.

Patented Jan. 13, 1852.

UNITED STATES PATENT OFFICE.

S. T. SANFORD, OF FALL RIVER, MASSACHUSETTS.

MACHINERY FOR PUNCHING SHEETS OF METAL.

Specification of Letters Patent No. 8,660, dated January 13, 1852.

To all whom it may concern:

Be it known that I, SAMUEL T. SANFORD, of Fall River, in the county of Bristol and State of Massachusetts, have invented an 5 Improved Machine for Punching Copper or Metal Plates; and I do hereby declare that the same is fully described and represented in the following specification and the accompanying drawings, letters, figures, and 10 references thereof.

Of the said drawings Figure 1 denotes a top view of my said improved machine. Fig. 2 is a side elevation of it. Fig. 3 is a central, vertical, and longitudinal section of 15 it. Fig. 4 is a transverse section of it.

In the said drawings A represents the punching cylinder or drum, which consists of a drum or cylinder having a series of punches or points *a, a, a, &c.* extended from 20 its periphery and made to enter during the revolutions of the drum corresponding recesses or holes *b, b, b, &c.* made in the surface of a bed cylinder or drum B arranged below the drum A as seen in the drawings, 25 the two drums are mounted in a supporting frame C, and have their shafts connected by two equal sized gears D, E, so that they may each revolve at the same speed, and the lower one be revolved when the upper 30 one is put in revolution. In connection with such drums I employ a carriage or movable frame F, which is supported and made to slide on parallel ways or rails G, H, the said carriage having a rack I of 35 teeth fastened on its upper surface near one edge of it as seen in the drawings. A pinion or gear K fixed on the shaft *c* of the upper punching cylinder engages with the said rack so that when a person lays hold of a 40 crank L (fixed on the said shaft *c*) and imparts to the said shaft a reciprocating circular motion, he will at the same time cause the carriage to move on its ways with a reciprocating rectilinear motion.

45 To the inner edges of the two side bars *d, e,* of the carriage, two long rest plates or rests M, M, are hinged by hinges as seen at *f, f,* and in such manner that they may each be turned down from a horizontal to 50 a vertical position. Each of these rests is supported when in a horizontal position on the upper end of a turning lever N, the said lever being made to be supported by and to turn on a fulcrum or pin *g,* projecting from 55 the inner surface of the side bar of the carriage. The lower arm of the lever projects

below the upper edge of the rail G or H, while to the upper arm two springs, *h, i,* are attached and extend in opposite directions from it as seen in Fig. 3, the outer ends 60 being secured to the carriage. These springs serve to bring the lever into an upright position after the force or power that inclines it may have ceased to act, the power of such springs being also sufficient to raise up the 65 rest piece that is over them. Each rail G or H is provided with two small studs or projections *m, n,* arranged and projected from its inner surface as seen in Fig. 3, each of the projections being so disposed as 70 to be in the path of the lower arm of the lever N, and to be met by the said arm directly after a sheet of copper placed on the rests has been passed longitudinally from end to end entirely between the two punching cylinders and been punched. 75

The above constitutes my said improved machine. Its operation may be thus described. While one workman lays hold of the crank and imparts a reciprocating circular motion to the punching cylinders and a reciprocating rectilinear movement to the carriage, another takes up a sheet of copper or metal and lays it on the two rests or flaps M, M, while they are in a horizontal 80 position. This done the sheet is carried between the two punching cylinders and after being punched with holes the lower arms or tails of the small supporting levers of the rests are respectively carried by the continued movement of the carriage against two of the studs *m, m* or *n, n,* and tripped so as to cause the levers to turn into a horizontal position and thus permit the rests to turn or fall down into a vertical position 85 90 and thereby discharge the sheet or allow it to drop off the same by the action of gravity. As soon as the carriage is next moved in an opposite direction the springs are suffered to act and elevate the levers into vertical positions and so as at the same time to elevate the rests into a horizontal position ready to receive another sheet of copper. Thus the sheets are laid on the rests of the carriage, carried between the punches or 95 punching cylinders and punched, and finally discharged from the machine the rests of which after the discharge of each sheet being brought up or reset ready to receive another sheet. 100 105 110

What I claim as my improvement is—
The combination of the hinged flaps M,

M, and their levers N, N, restoring springs and tripping studs or equivalent mechanic contrivances, with the movable carriage F and the punching cylinders or mechanism, the whole being arranged and made to operate substantially as hereinbefore specified.

In testimony whereof I have hereto set

my signature, this eighth day of December A. D. 1851.

SAMUEL T. SANFORD.
